UNITED STATES PATENT OFFICE.

SEBOLT J. SENIOR, OF WYMORE, NEBRASKA.

BED ATTACHMENT FOR VEHICLES.

Application filed September 6, 1922. Serial No. 586,504.

To all whom it may concern:

Be it known that I, SEBOLT J. SENIOR, a citizen of the United States, residing at Wymore, in the county of Gage and State of Nebraska, have invented certain new and useful Improvements in Bed Attachments for Vehicles, of which the following is a specification.

This invention relates to a folding bed, 10 and more particularly to such a bed adapted to be carried in its folded condition upon the running board of an automobile.

The invention has for its object the provision of a bed attachment for automobiles 15 which can be folded or collapsed with a mattress therein and carried upon the running board of the vehicle. Another object of the invention is the improvement of the details of such a bed attachment. A still 20 further object of the invention is the provision of a novel construction of hinged connection between the running board and the bedframe, whereby the bed may be easily removed from its connection with the vehicle but securely supported and locked upon the vehicle in its collapsed or folded condition. Other objects and advantages of the invention will hereinafter appear in the following description and the novel features 25 thereof will be particularly pointed out in the appended claims.

Like letters of reference indicate like parts throughout the several drawings, in which—

35 Figure 1 is a plan with bed torn partly away to show the arrangement of springs with relation to the framework;

Figure 2 is a side elevation of the bed in unfolded position;

40 Figure 3 is a perspective of a cross bar used in the folding of the mattress;

Figure 4 is an end view upon the line 4—4 of Figure 1;

45 Figure 5 is a section taken on the line 5—5 of Figure 1 to show the position of the central supporting legs;

Figure 6 is an end view of the hinged sides showing the radius of action;

50 Figure 7 is a section through the hinged connection between the bed frame and the running board;

Figure 8 is a section through the folded bed showing in dotted lines two positions assumed by the bed in its unfolding or setting up; and

55 Figure 9 is a perspective of the folded

bed upon the running board of an automobile.

It will be appreciated that the invention may be embodied in several forms, only one of which has been shown upon the drawing and described in this specification, and that the form so shown and described must therefore be considered as indicative only.

The invention consists of a sectional frame 65 comprising structural angles in which is mounted a typical form of bed spring, a mattress adapted to be spread in a peculiar manner upon the bed spring and folded within the collapsed framework, and a novel 70 mounting for the framework upon the running board of an automobile. These features will be now described in detail and their individual functions pointed out, after which a résumé of their conjoint use will 75 be given.

The framework 10 of my bed attachment is made in two sections 11 and 12 hingedly connected together at 13. The bed spring 14 of typical form is mounted within the 80 two sections and each section is made of side members 15, 15', and end members 16, 16', respectively, all of light angle iron.

Depending from the end member 16 are pivoted legs 17, 17' of short angle iron or 85 wood, which are adapted to be folded, as shown in dotted lines in Figure 4 within the angle of the end piece 16. Hinged to the side members 15, 15' are boards 18, 18, which are adapted to occupy the positions shown 90 in full and dotted lines in Figure 6, and to be held in the full line position shown in said figure by means of the cross bar 19, having the hooks 20, 20 at its ends. The boards 18, are notched at 21 for the purpose of receiving the hooks 20 and holding 95 said hooks against sliding movement upon the edges of the boards. There is an additional function for said cross bar 19 as will hereinafter appear.

100 Referring to Figure 5 it will be seen that the framework is provided centrally with a support 22 which comprises a cross bar having at each end a leg 23, an ear 24 and a brace 25, the brace member being attached at one end 26, to the cross bar and having its other end bent and apertured. The ear 24 is apertured in alignment with the aperture of the brace and the hinged bolt 27 passes through both said members as well 110 as through the side members 15, 15' of the bed framework. To insure the position of

the support 22 centrally in the set-up bed I have provided like chains 28, 28' connecting the lower ends of the legs 23 with the side angle member 15, 15'.

5 Referring to Figure 7 the numeral 29 indicates the running board of an automobile, to the under face of which has been attached a strip 30 of wood or other suitable material and lying against this strip 30 is 10 a pair of hinged members 31 having bill portions 32 terminating in lips 33 which lie slightly above and in parallelism with the strip 30. The hinge portions 31 and the strip 30 are attached to the running board 15 by the bolt 34, and it will be noticed that the strip projects slightly beyond the said running board, providing a ledge 35 upon which the angle member 16', will rest when the bed is being carried in its collapsed position by 20 the automobile.

As shown in Figure 7, when the bed is set up, all that is necessary to remove it from the automobile is to lift the angle member 16' from its position in the hooks 31 and 25 likewise it is only necessary in attaching the bed to the automobile to insert the angle 16' into the hooks 31. But when the bed is collapsed or folded, the angle member 16' will occupy the position shown in Figure 8 30 and in full lines in Figure 7, when it will rest upon the ledge 35 with its back against the edge of the running board and the end of one leg of the angle within the hook 31 under the lip 33. In this position of the 35 parts, it will be appreciated that the bed will be securely held to the running board without any danger of its removal by jar or shock.

As shown in Figure 1, when the bed is in 40 set-up position, the mattress extends from the end member 16 to and across the running board of the automobile, and it will also be seen that the upper face of the running board is in a plane with the upper 45 face of the bed framework, whereby the running board is utilized as a part of the bed upon which the pillow may be placed. When it is desired to fold or collapse the bed, that portion 36 of the mattress which 50 is on the running board is folded over into the dotted line position indicated by the numeral 36' in Figure 3. The side boards 18 are swung into their full line position of Figure 6, the cross bar put into place with 55 the hooks resting in the notches 21 and the portion 37 of the mattress folded over the said cross bar 19 and between the boards 18 into its dotted line position indicated by the numeral 37' of Figure 2. In this position 60 the mattress will be held as the bed is folded or collapsed into the position shown in full lines in Figure 8.

In order to set forth clearly the method of unfolding and refolding of the bed attachment, reference is made to Figure 8

wherein the frame is shown as folded in position upon the running board, being held there by strap 38 extending from any suitable position, as for instance the underface of the strip 30 to a hook 39 attached to the 70 body 40 of the automobile. The strap or band 38 may be made of elastic material if so desired.

Upon the removal of the strap 38, the bar 16 of the bed frame may be grasped and 75 pulled outwardly until it assumes the dotted line position indicated by 41 in Figure 8, and upon a further pull outwardly the bedframe will occupy the position shown by the numeral 42 in said figure, at which time the 80 legs 17 may very conveniently be dropped from their frictionally held position within the angles. It will be noted that in this movement of the frame that the legs 23 under the influence of the chains 28 and 28' have assumed a vertical position in respect to the bedframe and that when the bar 16 is finally lowered the legs 17 and 23 are in proper position to support the bed frame centrally and at one end. The other 85 end of the frame is supported by the hinged members 31.

From the foregoing description, the operation of my invention will be apparent. It 90 will only be necessary therefore to give a 95 résumé of the conjoint use of the several parts, for a complete understanding of the invention.

The bedframe made of hinged sectional members is easily applied to the running board of an automobile when it is desired to carry it upon a trip, by inserting the angle member 16' into the hinged members 31. In storing the bed, the boards 18 are in the 100 position shown in the dotted lines in Figure 2, but when the bed is in use these are dropped, as shown in the full line position 105 in said figure and the cross bar 19 has been removed.

Upon lifting the boards 18 and connecting them by the cross bar 19, folding the mattress end 36 over into its dotted line position 36' (Figure 2) and upon folding the mattress end 37 over the cross bar into its 110 position 37', the bed may be collapsed by a reversal of the movement described in connection with the showing of Figure 8, with the leg 17 folded within the angle of the member 16 and with the support 22 lying between the two sections of the angle framework, as shown in full lines in Figure 8.

The strap 38 may be provided at its lower end with a hook which will take into a suitable aperture in the angle member 16'. At the upper end it may be provided with 125 a buckle. In Figure 8 the strap is shown as applied and in position to hold the bed in place upon the running board of the vehicle.

It will be appreciated that by my invention there is provided an easily attached bed 130

for use in connection with touring in an automobile, and that I have provided a light structure of bed framework occupying a minimum of space.

Having described my invention, what I claim as new and desire to secure by Letters Patent is:

1. In a vehicle bed attachment, a bed frame comprising a pair of hingedly connected sections foldable upon a lifting of the hinge connection, and means for holding a mattress upon said bed folded frame comprising side boards attached to one section, and a detachable bar connecting said side boards over which the mattress is folded.
2. In a vehicle bed attachment, a bed frame comprising a pair of hingedly connected sections foldable against each other upon a lifting of the hinge connections, one end of said frame hinged to the running board of a vehicle, a mattress adapted to lie upon the frame and running board, side boards hinged to one section of the frame, a cross bar above the mattress for holding said side boards in elevated position, the running board end of said mattress being foldable

back upon the mattress body, and the opposite end of the mattress being foldable over said cross bar upon said mattress body, whereby said mattress may be carried in the folded bed frame in the travel of the vehicle.

3. In a vehicle bed attachment, the combination of a vehicle running board, a bed frame comprising an angle end bar, a hinge member projecting from the underside of said running board, and comprising an upwardly turned hook adapted to receive said angle end bar, and a strip in said hook projecting beyond the running board and forming a ledge for supporting said angle bar against the edge of the running board.

4. In a vehicle bed attachment, a bed frame comprising an angle end bar, hinge hooks and strips attached to the under surface of the vehicle running board, said hooks providing a lip with which the angle bar is adapted to engage, and said strip providing a supporting ledge for said angle bar while the outer edge of the running board provides a support for the back of said angle.

In testimony whereof I affix my signature.
SEBOLT J. SENIOR.
